UNITED STATES PATENT OFFICE.

ANGELO PERRI, OF GROVELAND, MASSACHUSETTS, ASSIGNOR TO REECE SHOE MANUFACTORY COMPANY, OF BOSTON, MASSACHUSETTS, A CORPORATION OF MAINE.

LASTING-MACHINE.

1,222,127.

Specification of Letters Patent. Patented Apr. 10, 1917.

Application filed May 15, 1916. Serial No. 97,516.

To all whom it may concern:

Be it known that I, ANGELO PERRI, a citizen of the United States, residing at Groveland, in the county of Essex and State of Massachusetts, have invented certain new and useful Improvements in Lasting-Machines, of which the following is a specification, reference being had therein to the accompanying drawing.

10 This invention relates to "lasting machines," and more particularly to a novel "wiping mechanism" for use in the lasting step in the manufacture of shoes.

In the lasting of shoes a sectional wooden "last" is usually employed for giving form to the shoe. The shoe upper is required to be assembled with the sole about the last, as a form, and the lasting process may comprise the steps of first "pulling-over" the flexible upper about the fore part of the shoe and thereafter "wiping" the extending side margins and the margins at the heel and toe. Such wiping consists in forcing, smoothing and pressing the overhanging material of the upper into place about the last and sole, where it may be suitably secured preparatory to subsequent operations including attachment of sole and upper. In my prior Patent No. 1,168,963, granted January 18th, 1916, I have shown a machine in which all of the above described steps or operations may be performed, the machine comprising a shiftable "jack" which holds the shoe, a pulling-over mechanism, and heel and toe wiping mechanisms.

The present invention pertains more especially to a wiping mechanism adapted to use at the heel end of the shoe, although various features hereof might be effectively otherwise employed; and the principal object of the present improvement is to afford a lasting machine which will be simple and durable in construction and of maximum efficiency and convenience in operation.

45 The present application, therefore, discloses one form or illustration of a heel wiping mechanism embodying the present invention and of a lasting machine including the same. The invention may be variously employed. As herein disclosed, it is more especially designed to be employed in a so-called "bed lasting" machine, in which the inverted shoe is inserted after having been pulled over and in which usually both

the heel and toe portions of the shoe upper 55 are wiped and secured. On the other hand, the mechanism hereof may be substituted in such a machine as that of said Patent No. 1,168,963 for the heel wiping mechanism there shown. Or the mechanism hereof 60 might, in some cases, if desirable, be employed by itself solely for the wiping of heels of shoes.

The heel wiping mechanism herein illustrated is shown for convenience of such design as to be particularly adapted to employment in a bed lasting machine, and for this purpose to be combined with a jack or work holder which properly holds the shoes, and a toe lasting or wiping mechanism arranged in suitable relation thereto. However, the toe wiping mechanism is not herein shown in complete detail, and neither is the jack mechanism, as these are the subjects of separate patent applications, to which reference should be made for further details. The toe wiping mechanism is completely illustrated and explained in my copending application Serial No. 83,540, filed March 11, 1916, and the jack mechanism in application No. 96,748, filed May 11, 1916.

Indeed, the shoe holding jack, toe wiping mechanism and the heel wiping mechanism are in reality combined as a single machine, and therefore the three patents may for convenience be considered in conjunction with each other.

Among the particular objects to which the present invention is directed is to provide a heel wiping mechanism adapted to 90 efficient and convenient use for the wiping of both shoes, that is, the right and left shoes of a pair. A machine which may be quickly changed over for this purpose is very advantageous in permitting both shoes 95 of a pair to be completed before operating on other shoes.

It is another object hereof to provide a lasting machine wherein the wiping mechanism may be bodily swung upon mountings 100 independent of the mountings of the jack and substantially about the apex of the wiper plate contour as a center in order to set the line of wiping action into proper relation or coincidence with the center line 105 of the shoe at the end.

Another object is to provide a lasting machine wherein the readjustment of the jack,

whether automatic or otherwise, for rights and lefts, performs an automatic adjustment upon the wiping mechanism to coöperate therewith; particularly that the lateral 5 swinging of the jack will reset the line of action of the heel wiping mechanism so as to lie in a line coincident with the center line of the heel part of the shoe.

Another object hereof is to provide a 10 wiping mechanism for one end of the shoe, particularly the heel end, adapted to co-operate with a shoe holding jack, and wiping mechanism for the other end, of the character described in my said copending 15 application; involving a jack capable of transverse swinging, so as to bring the shoe apex line always in the same longitudinal axis when readjusting for rights and lefts, or for changes in style, particularly a jack 20 which swings about a vertical axis near the shoe heel apex, so as to bring the shoe toe apex into line therewith, or to a particular point at which the toe wiping mechanism can be readily adjusted by a swinging motion 25 about the apex of the toe wiper contour into alinement with the shoe toe center line.

Another object is to provide such a heel 30 wiping mechanism capable of coöperating with such a jack by adjustment of the angle of wiping action about the apex of the heel wiper plate contour. This is contrary to a swinging adjustment about a fixed axis in the machine, wherein the axis would not advance and retreat with the heel wiping head.

Another object is to provide that the 40 transverse swinging of a shoe holding jack may automatically determine the angle of wiping action; so that adjustment of the jack to straighten the shoe apex line for shoes of different shape will correspondingly change the angle at which the heel wiping mechanism is set so as to bring it in alinement with the shoe heel center line.

Another object is to provide an automatic 45 adjustment of the heel wiping mechanism such that, when the jack is reversed in position when changing from right to left shoes, and vice versa, the wiping mechanism will 50 be correspondingly and symmetrically reversed.

Another object is to similarly provide that the reversal of the jack for lefts and rights shall automatically control or effect the 55 transverse tilt of the wiper plates.

Another object is to provide that, whenever the wiping mechanism is symmetrically reversed for changing from rights to lefts, and vice versa, this will automatically 60 determine or effect the reversal of the lateral tilt of the wiper plates.

Another object is to provide a wiping 65 mechanism capable of longitudinal tilting adjustment about a transverse axis extending substantially through or near the apex

of the wiper plate contour, so that changes of tilt will not substantially alter the altitude of the wiper plates.

Another object is to provide a wiping mechanism wherein the adjustment of the angle of wiping action, and also the adjustment of longitudinal tilt of the wiping plates, and also adjustment of the lateral tilt thereof, are all effected about axes passing substantially through or near the apex 75 of the wiper plate contour.

Another object is to provide mechanical connections for effecting respectively the longitudinal tilting and the lateral tilting 80 adjustments of the wiping mechanism, which will be simple, effective, and easy and convenient of operation.

Another object is to provide adjusting means operative independently of the main tilting mechanism for laterally tilting the 85 wiping plates about one edge or the other.

Another object is to provide means for advancing or setting back the initial wiper plate position, so that the plates will stand in proper position to the shoe when commencing the wiping operation.

Another object is to provide adjusting means for varying the spacing between the clamping pads at the sides of the heel to accord with different sizes and shapes of 95 shoes.

To the attainment of the above referred to objects and advantages the present invention consists in the novel lasting machine or wiping mechanism, and the novel features of arrangement, design, combination and detail herein illustrated or described and claimed.

The accompanying five sheets of drawings contain the following figures:

Figure 1 is what may be considered a general front elevation of a bed lasting machine comprising a shoe holding jack and toe and heel wiping mechanisms illustrating one form or embodiment of the present invention. This view corresponds with Fig. 13 of application 83,540 and with Fig. 1 of application 96,748.

Fig. 2 is a front elevation of the heel wiping mechanism or "head" shown in Fig. 1, 115 the parts set level rather than tilted.

Fig. 3 is a top plan view of the mechanism shown in Fig. 2, the parts set centrally rather than in position for lasting a right or left shoe.

Fig. 4 is a left elevation of part of Fig. 2.

Fig. 5 is a central, vertical, longitudinal section of the heel wiping mechanism and some of its supporting parts.

Fig. 6 is a plan showing the relation of 125 the jack and the wiping mechanism when in readiness to wipe the heel of a left shoe.

Fig. 7 is a right elevation of the heel wiping head.

Fig. 8 is a top plan view with a plate re- 130

moved to show the wiper plates and carrying and actuating mechanism.

Fig. 9 is a top plan view with another plate removed to show the heel clamping and actuating mechanism.

Fig. 10 is a diagram showing the position of certain parts of Fig. 7, reset to effect lateral tilt of the wiper plates.

Fig. 11 is a similar diagram showing in full lines the position of the same parts when swung and tilted for operation on a right shoe, and in dotted lines for a left shoe.

Fig. 12 is a heel view of a right last showing the angle of lateral tilt of the heel as compared with the ball; and

Fig. 13 is a corresponding view of a left last.

Generally speaking, a bed lasting machine such as that indicated herein may comprise a base 19, upon which are supported the jack or shoe holding mechanism 21, and to the right of the jack the heel wiping mechanism 22, and to the left of the jack the toe wiping mechanism 20.

Since the novelty of the invention is not restricted to the construction of the heel wiping mechanism, but lies also in the combination thereof with the jack and toe wiping mechanism, it will be necessary to describe the three mechanisms. The jack and toe wiping mechanism, however, being completely described in my copending applications, need not be so fully described herein. It will be convenient to first generally refer to the toe wiping mechanism, and subsequently describe the jack and the heel wiping mechanisms. The same reference numerals will be employed for all three patents.

Referring first to the toe wiping mechanism 20, the description in said application 83,540 may conveniently be condensed as follows:

At the left of the bed is an elevatable support 23, which may be lifted and lowered by a pedal 24 during wiping operations. Sliding on the support 23 is a carriage 25, which may be shifted toward and from the shoe by a hand-wheel 26. Upstanding from the carriage are brackets 30, which at their upper ends give support to the toe wiping mechanism or "head." At the extreme right of the toe wiping head is seen one of the wiper plates 61.

The movements and adjustments of the toe wiping mechanism are various. In addition to the longitudinal adjustment toward and from the shoe by the hand-wheel 26 and the lifting and lowering movements by the pedal 24, the toe wiping head 20 is capable of being bodily tilted longitudinally to different degrees from the horizontal by a hand-wheel 36. Also the wiper plates are designed to have operative movements toward and from the shoe, effected by hand lever

100 through carrier 50; the advance of the plates being accompanied by a convergence thereof and their retreat by a swinging apart or divergence. Another movement or adjustment, and one which is characteristic of this toe wiping mechanism, is an inversion, effected by handle 130, by which the single set of wiper plates is adapted from one shoe to the other, the inversion insuring symmetry of contour. Also, the advancing and retreating wiper devices are so arranged as to be adjustable to various inclines from the longitudinal axis of the machine. This is necessary from the fact that shoes are seldom straight, and the center line of the shoe 90 forepart extends at various inclines from the center line of the rear part. This is performed in a characteristic way, the swing of the mechanism taking place about a center substantially coinciding with the tip or apex of the contour of the wiper plates. The mechanisms are so combined and harmonized that the inversion of the wiper plates to reverse them in changing from one shoe to another simultaneously and symmetrically 95 reverses the direction or incline of wiping action.

The change of incline of wiping action is effected by mounting the wiper plates and their supporting devices upon a laterally shifting carriage 45, which engages with arc-shaped tracks struck about the center F, which is the apex of the contour of the wiper plates. The adjustment may be actually effected by hand-wheel 120 and suitable connections, which serve to throw the carriage 45 to or from a true longitudinal position to the degree required by the particular shoes being lasted.

Coming now to the jack mechanism 21, 105 this, as already explained, comprises shoe supporting devices permitting the shoe A to be swung horizontally about a vertical axis or center located at D near or approximately at the tip or apex L' of the shoe heel. 110 See Figs. 1 and 6. This permits the forepart of the shoe to be swung toward and from the operator, or transversely to the longitudinal axis of the machine in adapting it and the shoe to the toe wiping mechanism. 115 It has been explained that the adjustment of the angle of action of the toe wiping mechanism is performed about the point or center F as an axis, F being the apex of the contour of the toe wiper plates. This point, of 120 course, advances and retreats during the wiping movements. When the plates have been brought up into contact and conformation with the toe of the shoe, the apex F of the plates will coincide with the apex of the 125 shoe toe, which latter may be designated F'. See Figs. 1 and 6. Since the bodily adjustment of the toe wiping mechanism toward and from the shoe is longitudinal in direction, it follows that the point F, and there- 130

fore the point F', when the plates are in position to conform with the shoe, will always be in the longitudinal axis H of the machine. In other words, every shoe, straight or crooked, right or left, placed in this machine will be so located that the line F'-D joining the apexes of the toe and heel will be constant in location and direction.

In order to bring the shoe into the position indicated, the jack will be swung about the center D until the shoe toe apex F' lies in the longitudinal axis H-H. This will be indicated by the coincidence of the wiper plate apex F and the shoe toe apex F'. In this lateral swinging of the jack for rights and lefts and for different shapes and styles of shoes, the jack assumes different positions, which may be indicated by laying out the axis of the jack itself. This axis will seldom coincide with the longitudinal axis H-H; in fact, never, unless with an absolutely straight last. Thus, in the supposed instance the forepart of the jack has been swung out into the direction D-J, which represents the axis of the jack for the left shoe A. The adjustment of the toe wiping mechanism about the center F' is readily made, so that the wiper plate contour will conform with the shoe toe and so that the angle of wiping action will substantially coincide with the center line of the forepart of the shoe, as indicated.

The readjustment for a right shoe the mate of the left shoe A would be easily effected by a mere symmetrical shifting of both the jack and the wiping mechanisms.

When a change in shoe style is made, a different readjustment is made. The more nearly straight the shoe, the more nearly will the jack axis be adjusted toward the longitudinal axis.

With the above explanation of the character of the jack as it coöperates with the toe wiping mechanism the subsequent description of the relation of jack and heel wiping mechanism will be better understood.

The structure of the jack mechanism is sufficiently shown in Figs. 1 and 6. It comprises toe and heel rests 155 and 156 mounted at the upper side of a swingable base plate 157, which is of generally square form and located above the top plate or bed of the machine base 19. The jack base plate is transversely movable at the toe end by swinging about the center or vertical axis D, located substantially at or near the apex of the heel of a shoe or last held on the jack. The heel rest is adjustable on the base plate toward and from the toe rest. The base plate also carries a hold-down device comprising the hooked arms 170, which serve to clamp a shoe in position upon the toe and heel rests.

To permit the swinging movements referred to, the jack base plate, carrying the two rests and the hold-down device, is se-

cured to a vertical shaft 158 coincident with the axis D, before mentioned.

The details of the toe and heel rests and the hold-down mechanism are unnecessary to set forth in full, since *per se* they form no part of the present invention, but do form part of the invention claimed in said application No. 96,748, in which the same are fully described. It is sufficient to explain that a pedal 185 is employed, which controls the hold-down or clamp mechanism, the depression of the pedal pulling the hold-down hooks firmly upon the shoe and the parts becoming locked by a spring-pressed locking lever 196, releasable by its upper end or handle 197.

As further explained in said application No. 96,748, the depression of the pedal 185, acting through the lever 187 and connector or rod 189, serves not only to apply and lock the hold-down hooks, but also to lock the jack heel rest against longitudinal movement and the jack base plate against swinging movement.

To regulate the extent of swing or incline of the jack, which may be effected by hand or automatically, I may employ symmetrically adjustable stops, as explained in said application No. 96,748, adjusted by hand-wheel 203. Instead of throwing the jack across from one side to the other in changing from left shoes to right, and vice versa, an automatic arrangement may be employed for effecting this result at each operation of the pedal 185. Generally speaking, this mechanism operates by rocking the vertical fulcrum shaft 158 through a cam and roller device, actuated from the pedal through the lever 187 and connecting rod 211, as more completely described in said application No. 96,748.

The heel wiping mechanism or head 22 will now be more particularly described, this being of a character adapted to coöperate with the character of jack mechanism previously described, which in turn is adapted to coöperate with the character of toe wiping mechanism, previously described.

The coöperation between the jack and heel wiping mechanism is fourfold in the illustrated embodiment of the present invention.

Thus, firstly, the jack in accommodating a shoe to the toe wiping mechanism swings about the center D, which is located near or practically coincident with the apex L' of the heel of the shoe. By this arrangement the shoe swings during the adjustment, but the shoe heel apex L' is to all practical purposes fixed. In coöperation with this arrangement the heel wiping mechanism is arranged to bodily swing so as to change the angle of wiping action, this swinging being effected, not about a fixed axis in the machine, but about the apex L of the contour

of the heel wiper plates. This axis or apex L is a movable one, it being carried toward and from the shoe in the bodily adjustment longitudinally of the entire wiping head.

- 5 When the wiping head is brought up until the wiper plate contour conforms with the shoe heel, the apexes L and L' of course necessarily coincide, and the swinging adjustment of the wiper head about the apex L 70 readily and quickly permits the setting of the wiping action at the proper angle to suit the position of the shoe.

Secondly, a combination is involved wherein the setting or adjusting of the jack 15 to its proper incline automatically determines or effects the corresponding adjustment of the heel wiping mechanism as to its angle of wiping action. This arrangement, in making slight adjustments in the position of the jack to correspond with changes 20 in the style or curvature of shoes, relieves the operator from exercising his judgment in resetting the heel wiping mechanism to conform with the new angle at which the 25 shoe is held.

Thirdly, the reversal of the incline of the jack from one side to the other of the longitudinal axis of the machine in changing over from right shoes to lefts, and vice versa, determines or effects a corresponding reversal 30 of the heel wiping mechanism. This relieves the operator of one adjustment usually necessary in changing from rights to lefts, and vice versa, and therefore tends to 35 render more convenient and practical the plan of wiping right and left shoes alternately, so as to permit the completion of one pair of shoes before proceeding with another pair.

40 Fourthly, as shown in the accompanying drawings, the reversal of the jack, or throwing it across from one side to the other for rights or lefts, is caused to determine or effect the symmetrical reversal of the lateral 45 tilt of the heel wiping plates. It will be understood that for the first shoe of a pair the operator carefully adjusts the lateral tilt. When the other shoe is operated on, the tilt must be reversed, and this operation is 50 automatically taken care of herein through the act of reversing the position of the jack when one shoe is changed for another.

In fact, it will be observed that the operations of the pedal 185 in unclamping one 55 shoe and clamping the mate automatically perform the symmetrical reversal of the jack, and also the symmetrical reversal of the angle of heel wiping action, and also the symmetrical reversal of the lateral tilt of the heel wiping plates.

It will be convenient to describe in a general way the attainment of the above mentioned features of coöperation before describing the details of the heel wiping head. 65 As seen partly in dotted lines in Fig. 6, the

heel end of the jack base plate 157 is provided with a longitudinal extension or tail 231. Its upper side is provided with a longitudinal slot or guideway formed between opposing side parts 232. These side parts are 70 tapered at their rear ends to give an entrance to the guideway or groove. It will be understood that, whenever the jack swings transversely about the axis D for throwing the toe end thereof frontward or 75 rearward, the extending tail 231 will swing rearward or frontward, that is, reversely to the toe end of the jack.

The groove formed between the guide walls 232, 232, of the swinging jack extension is for the purpose of engagement by a stud or roller 230 extending downward between the guide walls from a transversely swinging carriage 228, fitted by means of curved ribs or guides 229 to receive a movement about the apex L of the heel wiper plate contour as a center. 80 85

The guiding extension 231 of the jack, therefore, either directly effects the swinging of the carriage from side to side, as required to adjust the angle of wiping action, or, if the stud 230 should have been retracted from engagement with the guiding extension, it determines the position of the carriage and wiping angle upon the reentry of 90 the stud into the groove between the guide walls 232, 232. Moreover, this swinging adjustment of the carriage 228 automatically takes place either in the case of a slight change in the jack incline for changes of 95 shoe style, or in the case of throwing the jack transversely across the machine from one side to the other in changing over from 100 rights to lefts, and vice versa.

The symmetrical reversal of the lateral 105 tilt of the heel wiping plates is effected, by connections later to be described, by the act of symmetrically reversing the carriage 228 and the line of wiping action; and is therefore either determined or effected by the adjustment or readjustment of the jack. 110

The heel wiping mechanism 22 may be described in detail as follows: At the end of the machine is arranged a rising and falling support 218 similar to the support 23 115 of the toe wiping head at the other end. The support 218 may be lifted or lowered to alter the altitude of the heel wiping head by means of a handle or crank 219 operating through a shaft 220 geared to a vertical screw shaft 221, having threaded connection with the rising and falling support. 120

At the top of the support 218 is a longitudinally sliding frame 223, by which the wiping head may be bodily shifted toward 125 and from the work. This frame 223 is slidably mounted in longitudinal ways on top of the support 218, similarly to the frame 25 at the other end, which carries the toe wiping head. To effect the longitudinal 130

shifting of the frame 223, it is provided with a toothed rack 224 engaged by a pinion on the shaft of a hand-wheel 225. A locking lever 226 is indicated, this serving to hold the frame leftward when adjusted to the work.

Above the longitudinally sliding frame 223 is a transversely swingable carriage 228. This travels upon curved bearing ribs or dovetails 229, which, as seen in Figs. 3 and 6, are struck about the apex L of the heel wiper plates as a center. By this arrangement the lateral swinging of the carriage 228 into different angular positions alters the angle of wiping action without changing the position of the center or apex L of the wiper plate contour. Downwardly extending from the swinging carriage is the stud or roller 230, previously mentioned, (see Fig. 5). This stud 230, as before explained, extends into engagement with the guiding extension or tail 231, for example, between the guide walls 232, which at the upper side of the extension form a guide groove, tapered at the extreme right end to facilitate the entrance of the stud thereinto.

By this construction the positioning of the jack determines or effects the transverse swinging of the carriage 228 and accurately sets the angle of wiping action to accord with the position in which the shoe may be held in the machine. In Figs. 1 and 6 the heel wiping head is shown moved to the left or brought up to the wiping position. When retracted by turning the hand wheel 225 to slide the entire frame 223 to the right, the stud 230 will easily pass out of engagement with the guide extension of the jack. The manual adjustment of the jack for changes in style may be effected while the head is thus retracted. The flaring entrance to the guide groove insures correct reengagement of the parts. The symmetrical reversal of the jack for rights or lefts is preferably effected while the stud is engaged in the guiding extension, in which case the transverse shifting of the jack actually effects the corresponding swinging about the center L of the carriage 228.

The carriage 228 is provided with upstanding side brackets 234 having trunnion bearings 235 at their upper ends, between which are tiltingly supported certain further parts to be described.

Directly trunnioned on the bearings 235 is what may be called a longitudinally tilting shell 237. This is generally of the shape of a portion of a ring, so as to afford circular bearing surfaces for the parts contained within, which are intended to be laterally tilted. The shell is irregularly shaped for accommodation with the various associated parts, but does not require a detailed description. One point, however, 65 which should be noted, is that the axis

about which the shell 237 tilts, namely, the axis of the trunnion bearings 235, is a transverse horizontal axis passing substantially through the apex L of the contour of the heel wiper plates. By this arrangement the righthand or rearward end of the shell may be lifted and lowered to secure adjustment of longitudinal tilt without substantially disturbing the elevation previously determined for the wiper plates. In other words, the adjustment of longitudinal tilt is effected about the apex of the wiper plate contour, thus greatly facilitating the adjusting operations. Fig. 2 shows by dotted line N—N a suitable degree of tilt, although for convenience in Figs. 2 to 10 the parts are illustrated without tilt. In Fig. 1 the toe and heel wiping mechanisms are both shown as slightly tilted, as required by the shape of the shoe or last.

Next will be described the laterally tilting carriage 240, which has a rocking movement within the circular shell 237; the actual connections for effecting the longitudinal tilting of the shell and the lateral tilting of the carriage being left to a later point.

The carriage 240, which is shaped to be accommodated within the concave interior of the shell 237, is a built-up structure comprising three flatwise plates, 241 beneath, 242 in the middle, and 243 forming a cover at the top. These three plates are rigidly bolted together to form a unitary structure, but are vertically spaced apart from each other to afford a horizontal space above the bottom plate to accommodate the fittings for the heel clamping devices, and a space between the middle plate and cover to accommodate the fittings of the heel wiper plates, including the carrier which is movable to 100 and from longitudinally to carry and actuate the wiper plates in the wiping operation.

The three constituent plates of the laterally tilting carriage are suitably provided with finished convex bearing surfaces 244 adapted to engage the finished interior bearing surface of the shell 237, and, indeed, the top and bottom plates are enlarged at 110 244 to give a more extended bearing surface.

The built-up carriage 240 is held against 115 longitudinal movement in the hollow shell by means of shoulders 245 near the forward or left ends of the plates and by attached triangular retaining plates 246 near the rear, (see Figs. 8 and 7).

Referring now to the heel clamping devices and their fittings contained between the carriage plates 241 and 242, the details are best seen in Fig. 9, top view, Fig. 4, left end view, and Fig. 5, central section. 125 These are arranged on a plan similar to that disclosed in Fig. 25 of my prior Patent 1,168,963, wherein a central clamp member or heel abutment pad at the longitudinal axis is adapted to meet the shoe or last as 130

the clamping mechanism is thrust toward the shoe, and by relative movement of a wedge or cam to force the side clamp members toward each other against the sides of the shoe or last. This action takes place when the wiping head is thrust bodily leftward by the hand-wheel 225, the parts becoming locked, as already explained, so that the shoe is rigidly clamped by the heel wiping head after the various tilting and swinging adjustments have been perfected and prior to the operative movements of the wiper plates.

Referring to the drawings, the central heel clamp member or pad 248, which may be termed an abutment, is pivoted at the forward extremity of the slide bar 249, arranged to slide longitudinally in ways 250 at the upper side of the lowest carriage plate 241. A spring 251 within a recess in the slide bar bears at its right end against a fixed screw, its forward end tending to press the heel abutment relatively leftward.

The slide bar 249 also carries a wedge cam 252, the action of which is to force the side clamp members together. This cam is axially pivoted to the bar to permit rocking of the cam for equalization of clamping pressure against the sides of the shoe. The side clamp members 254, like the rear member, are pivoted to permit rocking, and thus allow an equalizing adaptation to the shape of the shoe. Each side clamp member comprises a two-part block 255 consisting of upper and lower halves riveted together. The block 255 is pivotally connected by a head and socket joint 256 to its carrying lever 260. This permits horizontal rocking for purposes of adaptation. At the inside of each side clamp block are a plurality of clamp pads 257. Three of these are shown at each side. They are capable of rocking in a vertical direction about horizontal pivots 258 inclosed between the upper and lower halves of the clamp blocks 255.

Thus, the surface of each side clamp is capable of universal adaptation, each clamp being bodily capable of rocking as a whole horizontally about a vertical axis, and each of the several pads being capable of rocking vertically about a horizontal axis.

Springs 259 between the side clamp members 254 and their respective carrying levers 260 tend always to swing the clamp members into the position shown in Fig. 9, but to permit yielding in adapting themselves to the shoe.

The carrying levers 260 swing about pivot studs 261 located in the middle part of each lever, and the far extremities of the levers are provided with cam rollers 262 adapted to engage the wedge cam 252, previously mentioned. Springs 263 act upon the levers 260, tending to hold the rolls 262 against the cam.

By the described arrangement, when the heel wiping head is bodily thrust toward the shoe, the shoe heel is contacted by the abutment pad 248, with the result that the slide bar 249 moves relatively to the right, so that the wedge cam 252 thrusts the cam rolls apart and forces the side clamp members 254 toward each other. When the clamp members have become snugly seated against the heel of the shoe, the movement ceases and the parts are locked in position.

It is sometimes desirable to relatively adjust the side clamp members to allow for differences in the width of shoe heels, and to enable such adjustment I have provided means for slightly shifting the pivots of the side clamp member carrying levers. Each pivot stud 261 consists of an eccentric disk mounted at the top end of a short vertical shaft 265, rotating in the carriage bottom plate 241. The shafts 265 at the two sides extend downwardly through the bottom plate, where they are provided with toothed wheels 266. A worm shaft 267, having reversely arranged worms, engages the two toothed wheels, so that, when the shaft is turned by the hand-wheel 268, the pivot studs 261 are shifted symmetrically apart or together. As seen in Figs. 1 and 2, the brackets 234 are recessed to accommodate the worm shaft 267 and permit play thereof during tilting adjustments.

The heel wiper plates 270 have their fittings between the middle plate 242 and the cover plate 243 of the laterally tilting carriage 240. Fig. 3 shows them in top view, as also does Fig. 8, but with the cover plate removed. Fig. 4 indicates the wiper plates in left elevation, and Fig. 5 in central section.

Referring first to Fig. 8, the two wiper plates 270, 270, are seen to be mounted in a manner similar to that shown in Fig. 31 of my prior Patent 1,168,963, and claimed in claims 41 and 42 thereof. That is to say, the two wiper plates, although relatively swingable, present a continuous wiping edge at all times during the wiping action, the swinging being provided for by an annular bearing arrangement located at a substantial radius from the meeting point of the plates, which is preferably the apex L of their contour. Thus, the annular bearing herein is provided by slots 271 in the respective plates engaged by curved extensions or ribs 272, constituting the bearing and being formed or attached at the forward or left-hand extremity of an advancing and retracting carrier 272 in the form of a sliding bar arranged between guideways 273 at the top side of the plate 242.

The simultaneous and symmetrical swinging of the wiper plates toward and from each other may be effected by a curved rack 274 provided on each, these racks engaging 130

respectively the teeth of mutilated pinions 275 fulcrumed at convenient points at either side of the carrier bar 272. The members 275 may be considered as toothed bell crank levers having extensions or arms 276, the outer ends of which are held relatively stationary by means of rods or links 277.

By this arrangement the relative advancing movement of the carrier 272, that is, a movement toward the left in Fig. 8, serves not only to advance the wiper plates, but causes the rotation of the toothed members 275, which act on the racks 274 so as to swing the wiper plates in unison.

These actuating movements of the wiper plates may conveniently be effected by hand through the following connections: The top side of the wiper plate carrier 272 is provided with an upstanding block or boss 278, which passes through a longitudinally extending slot in the cover plate 243 and is connected by a link 279 with the operating hand lever 280 pivoted at 281 to the top side of the cover plate 243.

After the insertion of any given pair of heel wiper plates in the machine, it may be found that a slight bodily adjustment of them toward the work will give a more effective wiping. As will be seen in Fig. 8, when the wiper plates are retracted, their longitudinal edges come into direct contact or abutment with each other. While in this position they may be set bodily forward or toward the work, according to this invention, by slightly shifting forward the rods or links 277. These links extend from the toothed members 275 to an adjusting cross bar 282. If this cross bar be adjusted toward the shoe, such adjustment moves forwardly the links 279, the toothed members 275, the carrier 272 and the wiper plates, and also the operating lever and connecting link.

For convenience the adjusting cross bar 282 is fitted to a block 283, fitted between the same guideways 273, before mentioned.

An adjusting screw 284 passes through the block 283 and into the threaded portion of a lug 285 upstanding from the carriage middle plate 242. At the righthand end of the block 283 is provided a plate 286, which engages a groove or collars on the adjusting screw.

By this arrangement a slight initial adjustment of the adjusting screw 284 will alter, as described, the forward set or position of the heel wiper plates and actuating mechanism.

We come now to the connections and control mechanism by which the longitudinal tilt of the tilting shell 237 is effected and the lateral tilt of the tilting carriage 240. These mechanisms are herein for convenience, effectiveness and simplicity combined so that some of the parts through which the longitudinal tilting is effected are em-

ployed in the adjusting of the lateral tilting. Also, associated with such mechanisms are means whereby the reversal of the wiping mechanisms for rights or lefts automatically effects the lateral tilt in one direction or the reverse; also means for independently varying the lateral tilt by lifting or dropping the wiper plates at one side without changing their position at the other side of the heel.

The connections to be described extend in part from the longitudinally sliding frame 223, so that the swinging of the carriage 228 transversely of the frame will have an operative effect to reverse the connections with respect to the lateral tilt of the carriage 240. Other portions of the connections to be described extend directly to the laterally tilting carriage 240. The connections, in fact, are symmetrical and extend substantially to the two corners of the carriage 240 which are farthest removed from the wiper plates. By effecting the adjusting operations from these two corners, the corners may be raised or lowered in unison to change longitudinal tilt, or one may be raised or lowered relatively to the other for changing lateral tilt.

The longitudinal tilt is effected by a hand-wheel 288, (see particularly Fig. 7, right-hand elevation; also Figs. 3, 5 and 2). The hand-wheel is at the upper end of a threaded shaft 289, fitted against longitudinal movement in upper and lower bearings 290, formed integrally with a cross bracket 291 secured rigidly to the longitudinally slidable frame 223 on which the carriage 228 swings.

The rising and falling movements are effected by the hand-wheel 288 through a toggle lever arrangement at both sides of the threaded shaft. This is best seen in Fig. 7. A threaded block or nut 292 moves up and down on the shaft 289 when the hand-wheel is turned. This block is connected at either side by a link 293, extending upwardly at an incline to a pivot or stud 294. The toggle is completed by an arm 295 connecting the extremity of the bracket 291 with the pivot stud 294. It will thus be seen that the two pivot studs 294 at the front and rear sides of the axis of the machine will rise or fall in unison with the turning of the hand-wheel. These two studs are connected respectively to separated points at the righthand extremity of the carriage 240. Thereby the operation of the hand-wheel is to lift or drop the swinging extremity of the carriage and the longitudinally tilting shell 237, which supports it.

As before explained, there are two modes of effecting lateral tilting. The first effects a decided tilting, which is adapted to be symmetrically reversed when the swinging carriage is thrown across for changing from rights to lefts. The other adjustment is a

supplemental adjustment on a small scale adapted to slightly lift or lower one side edge of the wiper plates independently of the other in finally conforming the wiping mechanism to the shoe heel.

The laterally tilttable carriage 240 has secured to its bottom plate, as seen in Fig. 5, a rightwardly projecting bracket 298 of irregular shape having dovetails 299, on which are slidable a pair of blocks 300, held in place by a right and left threaded adjusting shaft 301, journaled in the bracket 298 and having at its front end a hand-wheel 302. Turning the hand-wheel throws the blocks 300 toward or from each other. Fig. 7 and the other figures shows the blocks spaced directly above the pivots 294, previously mentioned. In this adjustment there will be no lateral tilting, but, as will later appear, a readjustment by the hand-wheel 302 will effect a lateral tilting that will be automatically reversible upon changing over the machine from rights to lefts. The blocks 300 are connected by compound links 303 with the pivot studs 294. The blocks and links are connected by a sliding pivot arrangement, consisting of a slotted or yoked head 304 at the top of the link 303, engaged by a sliding plate 305 pivoted on the face of the block 300.

The sliding between the described parts is for the purpose of the final adjustment of lateral tilt, before mentioned. The top of the slotted head of the link 303 has fitted to it a thumb nut 306, which extends downwardly into threaded engagement with the sliding plate 305. The thumb nuts 306 at the two sides are shown adjusted to the same position, so that the links 303 are effectively of the same length and the wiper plates are level, having no lateral tilt. Turning either of the thumb nuts one way or the other will correspondingly lift or drop the wiper mechanism at that side for the purposes referred to.

It will now be explained how the turning of the hand-wheel 302 changes the lateral tilt of the heel wiper plates and how the change in tilt thus effected by the hand-wheel is automatically reversed in changing the machine over from rights to lefts. Observing Fig. 7, it will be seen that in effect we have a parallelogram of links. The studs or pivots 294 are relatively stationary, their position upon the sliding frame 223 having been determined by the hand-wheel 228. Extending upwardly from the pivots 294 are the links 303, which are parallel and which at their upper ends are pivoted respectively to the blocks 300. If, with the parts in this adjustment, the swinging carriage 228 is thrown to the rear or front, that is, to the right or left in Fig. 7, the links 303 will swing, but will preserve their parallelism and will maintain

the blocks 300 always at equal altitudes, so that the upper side of the parallelogram is always horizontal and the carriage 240 is not laterally tilted.

Suppose, however, the hand-wheel 302 is turned so as to throw the blocks 300 farther apart. This adjustment preferably will be made while the swinging carriage is in its proper wiping position. We may, however, suppose the adjustment to be made with the parts centralized, as in Fig. 7. When the blocks 300 are thrown apart, the links 303 will diverge and the arrangement of the parts may be diagrammatically represented as in Fig. 10. The links or arms 293 and 295 hold the pivots 294 rigidly over the frame 223. It is understood that the laterally tilttable carriage 240 is above and swings transversely of the machine when the carriage 228 swings. When the blocks 300 have been adjusted from each other, the links 303 diverge, as shown. As in Fig. 7, the parts are shown centrally positioned in Fig. 10. The swinging carriage has not been swung to either side of the axis.

Suppose, now, however, the swinging carriage to be swung to the rear of the machine, that is, to the right in Figs. 7, 10 and 11, the carriage 240 will be seen to take the tilted position shown in full lines in Fig. 11. This is owing to the non-parallelism of the links 303. Obviously the nearer the parallelism, the less the tilt; and the greater the divergence, the greater the tilt. This places it in the operator's power to readily adjust the tilt as desired.

Fig. 11 also illustrates the automatic reversal of tilt when the carriage 240 is swung across to the front side of the machine with the carriage 228. In this swinging operation the carriage 240 starts at the full line position shown in Fig. 11 and passes through the horizontal position shown in Fig. 10, and then to the dotted line position shown in Fig. 11. The reverse tilt there shown is necessarily equal or symmetrical to the tilt at the other side.

Figs. 12 and 13 show respectively right and left shoes held in proper position with the ball of the shoe substantially horizontal and indicating the opposite lateral tilts of the heel portions of the respective shoes. The lateral tilts illustrated in Figs. 12 and 13 for the shoe heels will be effected by the mechanism shown in Fig. 7, when adjusted as indicated by the diagrams, Figs. 10 and 11.

The operation of the mechanism herein described will be apparent from the foregoing description. The several hand-wheels and other adjusting devices will be employed according to the operator's judgment, so as to rapidly set the heel wiping mechanism properly to the shoe. The wiper plate operating lever 280 will then be worked

to effect the actual wiping. The more complete description of the operation of the machine as a whole, including the adjustments and shifting of the shoe holding jack, 5 are sufficiently explained in said application No. 96,748, and need not be recited here.

It will thus be seen that I have described a lasting machine or wiping mechanism embodying the novel principles of the present invention and attaining the objects and advantages thereof; and further advantages in the described structure will be apparent to those skilled in the art. Many matters of mere design, arrangement, detail or sub-combination may be variously modified without departing from the underlying principles of the invention, and, therefore, there is no intention to limit the present invention to such features excepting in so far as 10 the same are recited in the appended claims.

What is claimed is:

1. In combination, a shoe holding jack transversely swingable about an axis substantially at the apex of the heel of a shoe held therein, a heel wiping mechanism transversely swingable about an axis substantially at the apex of its wiping contour and laterally tilttable, and connections actuated by the swinging of the jack for controlling both the swing and the tilt of the heel wiping mechanism.

2. In combination, a shoe holding jack transversely swingable about an axis substantially at the apex of the heel of a shoe held therein, a laterally tilttable heel wiping mechanism, and connections actuated by the swinging of the jack for controlling the tilt of the heel wiping mechanism.

3. In combination, a shoe holding means, a heel wiping mechanism transversely swingable and laterally tilttable, and connections actuated by the swinging movement of the heel wiping mechanism for effecting the tiltting of the heel wiping mechanism.

4. In combination, a set of wiper plates, and mountings therefor to permit tilting and swinging movements, including a transversely swingable carriage, a laterally tilttable carriage, and a longitudinally tilttable member or shell, at least two of which adjust about axes passing through the apex of the wiper plate contour.

5. In combination, a set of wiper plates, 55 and mountings therefor to permit tilting and swinging movements, including a transversely swingable carriage, a laterally tilttable carriage, and a longitudinally tilttable member or shell, all three of which adjust about axes passing through the apex of the wiper plate contour.

6. In combination, a set of wiper plates, a base, a rising and falling member or carriage, and a longitudinally tilttable member 65 or shell partaking of the rising and falling

movements, said tilttable member fitted to swing about a transverse axis extending substantially through the wiper plate contour apex.

7. In combination, a set of wiper plates, 70 and mountings therefor to permit tilting and swinging movements, including a transversely swingable carriage, a laterally tilttable carriage, and a longitudinally tilttable member or shell, at least two of which 75 adjust about axes passing through the apex of the wiper plate contour, all said elements being movable in unison bodily toward and from the shoe; and means for holding a shoe in proper relation to said elements.

8. In combination, a shoe holding means, a heel wiping mechanism transversely swingable and laterally tilttable, and connections actuated by the swinging movement for effecting the tilting of the heel wiping 85 mechanism, such that when the machine is changed over from rights to lefts by symmetrically reversing the transverse swing of the wiping mechanism this effects a symmetrical reversal of lateral tilt.

9. In combination, a shoe holding means, a frame, a carriage transversely swingable over said frame, a carriage laterally tilttable over said swingable carriage, wiper plates carried on said tilttable carriage, and mechanism between said frame and tilttable carriage for causing the latter to tilt when said swingable carriage is swung.

10. In combination, a shoe holding means, a frame, a carriage transversely swingable 100 over said frame, a carriage laterally tilttable over said swingable carriage, wiper plates carried on said tilttable carriage, and mechanism between said frame and tilttable carriage for causing the latter to tilt when 105 said swingable carriage is swung, comprising arms pivoted below and above, and means for adjusting the degree of non-parallelism of said arms to alter the lateral tilt.

11. In combination, a shoe holding means, a frame, a carriage transversely swingable over said frame, a carriage laterally tilttable over said swingable carriage, wiper plates carried on said tilttable carriage, and mechanism between said frame and tilttable carriage for causing the latter to tilt when 115 said swingable carriage is swung, comprising non-parallel arms pivoted below and above, means for adjusting the degree of non-parallelism of said arms to alter the lateral tilt, and means for independently varying the effective length of an arm to change the lateral tilt.

12. In combination, a shoe holding means, 120 a frame, a carriage transversely swingable over said frame, a carriage laterally tilttable over said swingable carriage, wiper plates carried on said tilttable carriage, mechanism between said frame and tilttable carriage for 130

causing the latter to tilt when said swingable carriage is swung, comprising arms pivoted below and above, and means for independently varying the effective length of an arm to change the lateral tilt.

13. In combination, a shoe holding means, a frame, a carriage transversely swingable over said frame, a carriage laterally tilttable over said swingable carriage, wiper plates carried on said tilttable carriage, mechanism between said frame and tilttable carriage for causing the latter to tilt when said swingable carriage is swung, and means for supplementally varying the lateral tilt after the swing of the mechanism is effected.

14. In combination, a set of wiper plates, a laterally and longitudinally tilttable carriage therefor, a pair of depending links

symmetrically pivoted to said carriage, a pair of pivots at the lower ends of said links, 20 and means for changing the relative angle of said links to vary the lateral tilt of said carriage.

15. In combination, a set of wiper plates, a laterally and longitudinally tilttable carriage therefor, a pair of depending links 25 symmetrically pivoted to said carriage, a pair of pivots at the lower ends of said links, means for changing the relative angle of said links to vary the lateral tilt of said carriage, and means for altering the height 30 of said pivots to vary the longitudinal tilt of the carriage.

In testimony whereof, I have affixed my signature hereto.

ANGELO PERRI.
